UNITED STATES PATENT OFFICE

99,401

DESIGN FOR A GLOVE

Charles R. Kovar, Richmond Hill, N. Y.

Application November 14, 1935, Serial No. 59,544

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 of the drawing are respectively front and back views of a glove showing my new design.

The entire exposed surface of the glove is covered with alternating series of short ridges,

extending transversely and formed in the knitted fabric of which the glove is made. Each ridge of each series is disposed at an angle to the long axis of the glove. The design is further characterized by an integral wrist portion extending on a slightly flaring line at the inner edge of the glove and a semi-circular line on the outer edge of the glove; the margin of the open ended wrist portion being trimmed with a scalloped pleated ruching.

I claim:

The ornamental design for a glove, as shown and described.

CHARLES R. KOVAR.
